UNITED STATES PATENT OFFICE.

JULIUS LEEDDE, OF BALTIMORE, MARYLAND.

APPARATUS FOR TREATING REFRACtORY ORES.

No. 796,585.

Specification of Letters Patent.

Patented Aug. 8, 1905.

Application filed November 7, 1904. Serial No. 231,791.

To all whom it may concern:

Be it known that I, JULIUS LEEDDE, a citizen of the United States, residing in the city of Baltimore and State of Maryland, have invented certain new and useful Improvements in Apparatus for Treating Refractory Ores, of which the following is a full, clear, and exact description.

My invention relates to apparatus for treating refractory ores, the same being especially designed for the treatment of tellurides, sulfurets, arseniates, antimoniates, and phosphorets of iron, lead, copper, &c., containing the precious metals.

The object of the invention is to provide novel means for subjecting the ore to an oxidizing-flame in a furnace and simultaneously supplying thereto a cooling alkaline solution, whereby the ore is calcined and the formation of slimes which interfere with the subsequent treatment is prevented, whereby the formation of sulfates or acids which produce a film over the precious metals and prevent the successful action of chlorin and mercury thereon is prevented, whereby the base metals and other oxidizable compounds are oxidized, and whereby the ore is subjected to a chilling action, which serves to disintegrate the same, keep the temperature down, and prevent the volatilization of the precious metals.

It is a well-known fact that in the presence of tellurium and other base metals gold and silver volatilize at relatively low temperatures, and it is also known that roasting is the usual and most approved way for eliminating these base metals to prepare the ores for subsequent treatment. When the ores are roasted, however, a large portion of the precious metals is volatilized and carried off in the fumes. This is avoided by the use of my apparatus, as a sufficient oxidizing heat is employed for oxidizing the base metals, which heat is held under control and prevented from rising to such a degree as to volatilize the gold and silver. Furthermore, it is well known that when the ores are roasted according to the usual methods the precious metals become coated with a film of silicon or of sulfates, which prevents the further successful treatment of the ore by other reagents.

The details of the invention will hereinafter appear, and the novel features thereof will be set forth in the claims.

In the drawings forming part of the speci-

fication, Figure 1 is an elevation, partly in section, of the apparatus as a whole. Fig. 2 is a vertical central section of the furnace. Fig. 3 is a top plan view of the same, with the cover or dome removed. Fig. 4 is a side elevation of the furnace. Fig. 5 is a detail sectional view of the distributer for the alkaline reagent. Fig. 6 is a cross-section on the line 6 6 of Fig. 5. Fig. 7 is an end view of the distributer. Fig. 8 is a detail sectional view on the line 8 8 of Fig. 5. Fig. 9 is a plan view of the furnace-bottom with sections of the same removed. Fig. 10 is a detail sectional view on the line 10 10 of Fig. 9. Fig. 11 is a section on the line 11 11 of Fig. 9. Fig. 12 is a longitudinal sectional view of one of the burners or twyers; and Fig. 13 is a section on the line 13 13 of Fig. 12, showing a plurality of the burners clamped together.

Like reference-numerals indicate like parts in the different views.

My improved apparatus comprises a furnace made up of a base-plate 1, supported in raised position upon the uprights 2 and having built up upon it the sides 3 and top 4 of fire-brick. The said base-plate has been shown as rectangular in shape and provided with an upwardly-extending flange 5 around its outer edge. It is preferably made of a metal casting bolted or otherwise secured to the uprights 2; but it is obvious that the same may be made of other material and be otherwise shaped and supported. At the center of the base-plate 1 is formed a circular opening 6, within which the bottom 7 of the furnace fits. The said bottom is mounted for rotary movement, is capable of being raised and lowered, and is supported upon a carriage or truck 8, by means of which it may be moved bodily up to and away from the body of the furnace. The furnace is mounted in elevated position in order to provide for these movements of said bottom. The truck or carriage 8 is provided with wheels 9, which move upon the rails 10, located between the uprights 2, beneath the base-plate 1, and extending to any suitable point.

Mounted in suitable bearings on the carriage 8 is a vertically-disposed shaft 11, the said shaft carrying a horizontally-disposed worm-gear 12, adapted to mesh with a worm 13, mounted in a suitable bracket or support 14 and driven in any suitable manner. The

said worm is fixed in position, and an adjustable stop 15 is provided for limiting the movement of the carriage 8 upon the rails 10 and determining the proper position of said carriage, so that the gear 12 will be in mesh with the worm 13 and so that the bottom 7 will be directly beneath the opening 6 in the base-plate 1. Ball-bearings 16 are provided between the gear 12 and the carriage 8, and said gear has a key connection 17 with the shaft 11, so that while said shaft is rotated by said gear it is also capable of vertical movement independent of said gear.

Secured to the upper end of the shaft 11 is a sleeve 18, upon which are cast or otherwise secured the outwardly and upwardly curved arms 19, the latter having bolted or otherwise secured to them a hollow frame having a central circular portion 20 and radiating ribs 21. These ribs are formed with recesses providing the shoulders 22 and have lugs 23 formed upon them. Within said recesses and supported upon said shoulders are the triangular plates 24, the same being secured to said ribs by bolts extending through said lugs. The said triangular plates or sections 24 and the ribs 21 form the bottom 7 of the furnace, each of said plates or sections being provided with an upwardly-projecting flange 25 around its outer edge. Upon the central circular portion 20 of the hollow frame referred to is secured an upwardly-extending hollow thimble or projection 26, which forms, with the flanges 25, an annular receptacle in the bottom 7. One of the sections 24 of said bottom is provided with an opening for the discharge of the contents of the furnace, the said opening being normally closed by a hinged door or trap 27. This door is pivoted at its outer edge and is adapted to swing downwardly, being held in its normal raised position in any suitable manner. I have shown the inner end of said door, however, provided with a lug or projection 28, adapted to receive a removable bolt 29, extending through said projection and through a lug on the under side of the section 24.

In order to provide for the elevation of the rotating bottom or table 7 of the furnace, I employ a hydraulic jack, shown in Fig. 2 of the drawings as consisting of a cylinder 30, having a piston 31 therein, with a plunger 32 on said piston adapted to engage the lower end of the shaft 11 and having a pipe 33 leading into the lower end thereof through which water or other liquid under pressure may be passed. This jack is of course located beneath the shaft 11 when the parts are in the positions in which they are shown in Figs. 1, 2, and 4 of the drawings.

Arranged within the combustion-chamber of the furnace are a series of burners or twyvers 34, the same being shown in two rows, with the members of each row parallel to each other in line with those in the other row and terminating at their inner ends a short dis-

tance from the longitudinal central line of the furnace. These twyvers or burners are all connected with a main supply-pipe 35 for fuel through the branches 36 36 of said pipe, which extend along the opposite sides of the furnace. The fuel-supply pipe 35 has been shown as extending from a gas-producer 37, the particular construction of which will not be herein described as the same forms the subject for a separate application for patent. It is sufficient to say with respect to said gas-producer that a valve or damper 38 is provided at the rear end of the retort whose position may be adjusted by means of the screw-rod 39 for admitting to and mixing with the gas before it leaves the generator any desired proportion of air, so that exactly the kind of oxidizing-flame which is desired may be produced at the burners 34. The said burners are provided with water-jackets and are so constructed that any one or more of them may be disconnected from the supply-pipes 36 without the necessity for completely dismantling the whole apparatus or removing any other parts. Each of said burners is horizontally disposed and located directly above the mass of ore upon the bottom 7, the jets of flame therefrom issuing downwardly. Each is provided with a central passage or chamber 40, having a series of downwardly-facing burner orifices or openings 41 on one side thereof, and each is provided with a water-chamber 42, extending from end to end thereof and located above and below the passage 40. The outer end of each of said burners is formed with a transversely-extending tube or sleeve 43 of the same diameter as the pipe 36, the said sleeve communicating with the central passage 40 and having flanges 44 thereon, by means of which it may be bolted or otherwise secured to corresponding flanges on adjacent burners or to the flanges 45 on the pipe 36. Each of said burners is also provided with transversely-extending tubes or sleeves 46 47, the upper of which is formed with end flanges 48 and the lower of which is formed with end flanges 49. These flanges 48 and 49 are adapted to be bolted or otherwise secured to corresponding flanges on adjacent burners or to flanges 50 51 on the pipes 52 and 53, respectively. Each of the pipes 52 and 53 is formed with two branches which extend along the sides of the furnace parallel with the branches 36 of the fuel-supply pipe 35, said pipes 52 and 53 also extending upwardly to a water-supply tank. When the different burners or twyvers 34 are connected to each other and to the pipes 52 and 53 in the manner described, the tubes or sleeves 43 will form continuations of the pipe 36, and the tubes or sleeves 46 and 47 will form continuations of the pipes 52 and 53, respectively. As the pipes 52 and 53 are connected with the water-tank and as the chamber 42 communicates with the sleeves or tubes 46 and 47, it will be noted that a

water-jacket will be formed around each of the burners or twyers, the circulation being created in the usual manner. It will also be noted that a supply of fuel will be delivered through the pipe 35, its branches 36, the tubes or sleeves 43, and the passage 40 to the burner-orifices 41. As the burner proper, however, is water-jacketed, it will be impossible for the same to be raised to a red heat or be otherwise overheated. Consequently no ignition of the fuel-gas within the burners or twyers can take place. This is a great objection to other forms of apparatus of this kind. In case the necessity for repairs arises any one or more of the burners or twyers 34 may be disconnected from the adjacent ones by removing the securing-bolts which hold it in place and a new one substituted without the necessity for disconnecting any of the other parts of the apparatus. The burners rest near their outer ends upon the chairs 54, cast or otherwise formed upon base-plate 1, and said burners are also provided with laterally-extending lugs 55, through which and corresponding lugs on the base-plate 1 additional securing-bolts are passed.

I employ in connection with the above parts a distributer 56 for an alkaline cooling solution. This distributer is most clearly shown in Figs. 2, 3, 5, 6, 7, and 8 of the drawings. The same comprises a tubular body having a series of holes or perforations 57 in the bottom thereof and means for controlling the passage through said holes. Said body has been shown as rectangular in cross-section with one corner cut away; but it may be of any other suitable shape. The distributer is horizontally disposed and extends from front to rear of the furnace, being located in the space between the inner ends of the burners or twyers 34 and being bolted to the base-plate 1. The opposite ends of the body thereof have respectively connected to them and communicating with the interior of the body the pipes 58 and 59, which lead from an elevated tank or other suitable source of alkali reagent, so that the distributer is kept charged with said reagent at all times and by the circulation that is created the reagent is kept in a comparatively cool condition. The holes or perforations 57 are reamed out or otherwise enlarged at their upper ends, and adapted to fit within them are the pins 60, having correspondingly-shaped tapering lower ends, one of such pins being provided, of course, for each of said openings or perforations. The said pins are all carried by a block 61, located within the body of the distributer and mounted for bodily movement up and down. The said block is guided in its movements by means of the guide-pins 62, which extend through openings in said block. Extending through the body of the distributer 56 and mounted in suitable bearings in the ends thereof is a shaft 63, having a rec-

tangular extension 64 on one of its projecting ends adapted for the application of a key or wrench for turning said shaft. Within the body of the distributer the shaft 63 is provided with crank-arms 65, which are connected through the links 66 with the block 61, on which the pins 60 are carried. It will thus be seen that by turning the shaft 63 in one direction or the other the block 61 may be raised or lowered, the latter being guided in a direct vertical line by the pins 62. When the block is raised, the pins 60 are lifted from their seats in the holes or perforations 57 and the passage through said holes or perforations is opened. Through the latter the alkaline cooling reagent is discharged and of course the degree of the discharge may be readily controlled and regulated by adjusting the position of the block 61, which adjustment may be effected by adjusting the position of the shaft 63. The pins 60 are loosely mounted in the block 61, so that they are capable of vertical movement independent of said block. The downward movement of each is limited, however, with respect to said block by a flange or shoulder 67, and each of the same is normally urged downwardly by means of a coil-spring 68, which fits within a recess in the block 61 and bears against a shoulder at the rear of the head of the pin. By this construction clogging of one of the holes or openings 57, which would prevent the entrance of the lower end of the pin 60, which co-operates therewith, will not prevent the other pins from entering into and closing the openings 57, with which they respectively co-operate. The end of the shaft 63, which is provided with the rectangular extension 64, carries a ratchet-wheel 69, with which co-operates a spring-actuated dog 70, mounted upon the end of the distributer. This dog, acting upon said ratchet, serves to hold the shaft 63 in any position to which it may be turned by a key or wrench applied to the rectangular extension 64, and consequently holds the block 61 and the pins 60, which control the passages 57, through which the alkaline cooling reagent is discharged, in adjusted position.

From the top of the furnace leads a chimney or flue 71 for the escape of the products of combustion and other fumes. This flue is connected with a condenser 72 for recovering from the fumes any of the volatilized precious metals which may be carried off therein. The said condenser consists of a vertically-disposed pipe or conduit 73, to which the flue 71 is connected at the upper end. Within this conduit is located a pipe 74, having a series of spraying-nozzles 75 arranged at different points therein, the said pipe leading from a tank or other source of supply for a suitable liquid cooling and condensing reagent. The lower end of the conduit 73 fits within a drum 76, from the inclined bottom of which leads

a pipe 77 to a tank 78. The said tank contains near its upper end a pair of parallel screens 79 80, between which is located a mass 81 of crushed charcoal or other suitable filtering substance. An overflow-opening 82 is provided above the upper screen 79, and openings 83 for draw-off plugs are provided beneath the lower screen 80. The pipe 77 extends through the filter and discharges into the tank at a point just below the screen 80. Those portions of the fumes which are condensed in the conduit 73 pass down through the drum 76 and pipe 77 into the lower part of the tank 78, which contains water. The heavier particles will of course be precipitated to the bottom of the tank 78, and the filter 81 will prevent the escape of any condensed particles held in suspension from passing off through the discharge or overflow opening 82. Adjacent to the conduit 73 is a casing or inclosure 84, containing a series of filters arranged one above the other, each consisting of a perforated support 85 and a mass of crushed charcoal or other filtering substance 86 thereon. The drum 76 is connected with the lower end of the casing 84 by means of a pipe or coupling-piece 87, and a pipe 88 connects the lower end of the casing 84 with the tank 78 at a point in said tank beneath the screen 80. An escape-flue 89, preferably connected with an exhaust-fan, is provided at the upper end of the casing 84, and extending through the top of said casing are the spraying-nozzles 90, connected, through the pipe 91, with any suitable source of cooling or condensing reagent. Through the nozzles 90 the liquid reagent is supplied to the various filters in the casing 84, the same acting to keep such filters in moist condition. Any of the fumes which are not condensed in the conduit 73 pass through the pipe or coupling-piece 87 into the lower end of the casing 84 and then pass upwardly through one or more of the filters in said casing. These filters serve to more completely remove the valuable constituents from the fumes, so that nothing of real value escapes through the final discharge-flue 89. Such liquid as may percolate through the various filters and fall to the bottom of the casing 84 passes through the pipe 88 into the tank 78, there to be concentrated in the manner heretofore described. The filtering material 86 from each of the supports 85 in the casing 84 may be removed for the recovery of the valuable substances which accumulate thereon through the openings 92, as may also the filtering material 81 in the tank 78.

The operation of my improved apparatus is as follows: Fuel-gas is admitted to the various burners or twyers 34 through the supply-pipe 35, its branches 36, and the tubes 43 on said burners, which form continuations of said branches, and ignited at the burner-orifices 41. An oxidizing-flame is produced, and

by regulating the supply of air mixed with the gas from the producer 37, which may be done by opening or closing the damper 38 to a greater or less degree, a vapor-fuel may be obtained which is of exactly the quality desired. After ignition of the gas at the burners or twyers 34 the furnace is allowed to become thoroughly heated up and then is supplied with a charge of ore. The ore is preferably broken to about the size of stove-coal, the exact size being determined by the quality, kind, and condition of the ore to be treated. This charge is delivered directly upon the bottom 7 while the latter is at a point removed from the stationary part of the furnace, after which the truck or carriage 8, upon which the bottom 7 is mounted, is rolled along the track 10 until it strikes against the adjustable stop 15. At such time the gear 12 will be in mesh with the worm 13 and the bottom 7 will be directly beneath the opening 6 in the base-plate 1. A supply of water or the like under pressure is then admitted through the pipe 33 to the cylinder 30 of the hydraulic jack, and the piston 31 thereof is elevated. The latter acts, through the plunger 32, to raise the shaft 11 and the bottom 7 and to hold the latter in its proper position within the opening 6 in the base-plate 1. The worm 13 is then thrown into operation, and the latter, through the gear 12 on the shaft 11, serves to rotate the bottom 7. The top of the ore is directly beneath the burners or twyers 34, and as the jets of flame issue from said burners downwardly the said flame is caused to impinge upon the upper surface of the mass of ore and eventually to thoroughly calcine the same and oxidize the oxidizable portions thereof. When the furnace is charged in the manner described, the shaft 63 is turned so as to raise the block 61 and the pins 60 carried thereby and open the passages through the holes 57 in the distributer 56. The cooling alkaline solution in the distributer, which is supplied from the pipe 58, is then discharged through the holes 57 onto the top of the ore. The action of this alkaline solution is two-fold: First, it cools down the ore and prevents the temperature from rising to such a degree as would volatilize the precious metals contained therein, and, second, it neutralizes the acids in the ore and prevents the formation of sulfates and the like on the precious metals. It has the further effect of intermittently imparting a chilling action to the ore, which action serves to disintegrate the same. The supply of this cooling alkaline solution is continuous; but as the distributer 56 is fixed in position and the bed of ore is rotated the different parts of the ore will receive the impact of said cooling reagent but twice during each complete rotation of the mass. The operation just described is kept up for a suitable length of time, which may be determined by the observation of the operator when the ore

is removed for further treatment. When removed, the ore will be found to be thoroughly calcined and with no acids or sulfates therein which produce a film on the precious metal. The thorough calcining of the ores prevents the formation of slimes, which interfere with the subsequent treatment, the alkaline solution which is supplied prevents the formation of the sulfates or acids, and the cooling action which is effected by said solution keeps down the heat of the furnace and prevents the volatilization of the precious metals. To remove the ore from the furnace, the bottom 7 is lowered by relieving the pressure on the piston 31 of the cylinder 30, and the truck or carriage 8 is rolled out of the way to any suitable point on the rails 10. The ore may be dumped from the bottom by releasing the bolt 29, which holds the gate or door 27 in place and allowing the latter to fall. All valuable constituents of the fumes are removed in the manner heretofore described.

Having described my invention, I claim—

1. In an apparatus for treating refractory ores, a furnace-chamber, a series of burners or twyers therein provided with means for subjecting the ore in said furnace to an oxidizing flame, from above, and means for supplying to the ore in said furnace an alkaline cooling reagent.

2. In an apparatus for treating refractory ores, a furnace-chamber, a series of burners or twyers therein, arranged in rows, having their discharge-orifices directed downwardly for subjecting the ore in the furnace to an oxidizing-flame, from above, and an elongated hollow liquid-distributer located in said furnace in the space between the rows of burners.

3. In an apparatus for treating refractory ores, a furnace-chamber, a series of burners or twyers therein, connected with a suitable source of fuel, arranged in rows extending from opposite sides of said chamber, and terminating at their inner ends adjacent to a diametrical line through said chamber, and an elongated tubular liquid-distributer in said furnace located in the space between the ends of the rows of burners.

4. In an apparatus for treating refractory ores, a furnace-chamber, a rotary bottom therefor, a series of burners or twyers arranged in rows in said chamber, the inner ends of said burners terminating adjacent to a diametrical line through said chamber, and a hollow stationary liquid-distributer located in the space between the inner ends of said rows of burners.

5. In an apparatus for treating refractory ores, the combination with a furnace-chamber and means for roasting ores therein, of a liquid-distributer in said chamber comprising a hollow body connected with a source of liquid-supply and provided with a series of discharge-openings, and adjustable means in

said openings for controlling the discharge of liquid therethrough.

6. In an apparatus for treating refractory ores, the combination with a furnace-chamber and means for roasting ores therein, of a liquid-distributer in said chamber comprising a hollow body connected with a source of liquid-supply and provided with a series of discharge-openings, plugs or pins controlling the passages through said openings, and means for adjusting the position of said plugs for controlling the discharge.

7. In an apparatus for treating refractory ores, the combination with a furnace-chamber and means for roasting ores therein, of a liquid-distributer in said chamber comprising a hollow body connected with a source of liquid-supply and provided with a series of discharge-openings in its bottom, plugs or pins controlling the passages through said openings, a block upon which said plugs are severally mounted and means for regulating the position of said block and thereby controlling the passages through said openings.

8. In an apparatus for treating refractory ores, the combination with a furnace-chamber and means for roasting ores therein, of a liquid-distributer in said chamber comprising a hollow body connected with a source of liquid-supply and provided with a series of discharge-openings in its bottom, plugs or pins controlling the passages through said openings, a bodily-movable block on which said plugs are severally mounted, a guide for controlling the movements of said block and means for adjusting the position of said blocks for controlling the passages through said openings.

9. In an apparatus for treating refractory ores, the combination with a furnace-chamber and means for roasting ores therein, of a liquid-distributer in said chamber comprising a hollow body connected with a source of liquid-supply and provided with a series of discharge-openings in its bottom, a vertically-movable block in said body having recesses therein, a series of plugs or pins for controlling the passages through said openings, said plugs having heads thereon which fit in said recesses, and contracted shanks which extend through openings in said block, springs in said recesses for normally urging such plugs downwardly with respect to said block, means for limiting this downward movement and means for adjusting the position of said block and thereby controlling, through said pins, the passages through said openings.

10. In an apparatus for treating refractory ores, the combination with a furnace-chamber and means for roasting ores therein, of a liquid-distributer in said chamber comprising a hollow body connected with a source of liquid-supply and provided with a series of discharge-openings in its bottom, plugs or pins controlling the passages through said openings, a

bodily-movable block on which said plugs are severally mounted, a shaft mounted for turning movement in the ends of said body, crank-arms on said shaft connected with said block, and means for locking said shaft in any position to which it may be turned.

11. In an apparatus for treating refractory ores, the combination with a furnace-chamber and means for roasting ores therein, of a liquid-distributer in said chamber comprising a hollow body connected with a source of liquid-supply and provided with a series of discharge-openings in its bottom, plugs or pins controlling the passages through said openings, a bodily-movable block on which said plugs are severally mounted, a shaft mounted for turning movement in said body, a ratchet-wheel on said shaft, a dog on the body coöperating therewith, means for turning said shaft, and crank-arms connecting said shaft with said block.

12. In an apparatus for treating refractory ores, the combination with an elevated furnace-chamber having an opening in the lower part thereof, of a bottom for said chamber adapted to fit within said opening, a bodily-movable truck or carriage on which said bottom is mounted and means for raising and lowering said bottom, independently of said truck, into and out of said opening.

13. In an apparatus for treating refractory ores, the combination with an elevated furnace-chamber having a circular opening in the lower part thereof, of a circular bottom adapted to fit within said opening, a bodily-movable truck or carriage on which said bot-

tom is mounted, means for raising and lowering said bottom independently of said truck and means for rotating it.

14. In an apparatus for treating refractory ores, the combination with an elevated furnace-chamber having a circular opening in the lower part thereof, of a trackway beneath said chamber, a truck or carriage movable on said trackway, a vertical shaft mounted for rotation on said truck, a circular bottom for said furnace-chamber secured to and supported upon said shaft and adapted to fit within said opening, and means for raising and lowering said shaft and the bottom carried thereby, independently of said truck.

15. In an apparatus for treating refractory ores, the combination with an elevated furnace-chamber having a circular opening in the lower part thereof, of a trackway beneath said chamber, a truck or carriage movable on said trackway, a vertically-movable shaft mounted for rotation on said truck, a vertically-immovable worm-gear carried by said truck and keyed to said shaft, a worm adapted to mesh with said gear for turning it, means for raising and lowering said shaft and holding it in raised position and a circular bottom for said chamber mounted upon the upper end of said shaft and adapted to fit within said opening.

In witness whereof I subscribe my signature in the presence of two witnesses.

JULIUS LEEDE.
